UNITED STATES PATENT OFFICE

PAUL W. DILLON, OF STERLING, ILLINOIS, ASSIGNOR TO NORTHWESTERN BARBWIRES CO., OF STERLING, ILLINOIS, A CORPORATION OF ILLINOIS

WIRE DRAWING MACHINE

Application filed December 5, 1927. Serial No. 237,745.

This invention relates to a wire drawing machine and consists in certain improvements for facilitating and improving the operation thereof and which improvements 5 consist in means for automatically throwing out the clutch and stopping the machine if a link or loop is formed in the wire before it reaches the first die, in means for clamping the wire during the threading operation, in means for applying a brake when the clutch is thrown out, in means for driving the machine at the rear end thereof whereby the power is reduced, and in the use of a horizontal winding reel to facilitate 10 and render less laborious the removal of the drawn coil of wire.

The invention comprises the novel structure and combination of parts hereinafter described and more particularly pointed out 15 and defined in the appended claim.

In the accompanying drawings which illustrate a preferred embodiment of this invention and in which similar reference numerals refer to similar features in the different views:

Figure 1 is a side elevational view of a wire drawing machine involving this invention.

Figure 2 is a top plan view of the machine, 30 Figure 3 is a sectional view taken upon the line III—III of Figure 2.

Figure 4 is a sectional view taken upon the line IV—IV of Figure 2.

Figure 5 is a detail view of a portion of 35 the machine bench looking downwardly and illustrating the wire clamping means.

Figure 6 is a vertical elevational view of the structure shown in Figure 5.

Figure 7 is an enlarged sectional view 40 taken upon the line VII—VII of Figure 4.

Figure 8 is an enlarged sectional view taken upon the line VIII—VIII of Figure 3.

In referring to the drawings, there is illustrated a wire drawing machine embodying 45 the improvements involving this invention. In the drawings (Figure 1), the numeral 1 represents the initial or first drawing die through which the wire is drawn by a drawing drum 2. The second die is represented by the numeral 3 through which the wire is

drawn by the second drawing drum 4. The third drawing die 5 through which the wire is drawn by the drawing drum 6 is located near the rear of the machine. From the fourth drawing die 7, the drawn wire passes 55 around the storage reel which is horizontally arranged and which draws the wire through the fourth or last die. Above each drawing drum, there is an overhead guide roll 9 over which the wire respectively passes from each 60 drum as is well known in the art.

In connection with the aforementioned drawing dies, one or more clamps 10 may be used for clamping the wire during the threading operation. For example, after the wire 65 has been threaded through the die 3, it is wound around the drum 4 and the end inserted under the clamp 10 adjacent the die 3, for the purpose of holding and retaining the same. This clamp is best illustrated in Figures 5 and 6 and in referring to said figures, 70 it will be noted that the said clamp consists of a resilient metal strip pivoted to the die support by means of a pivot 11 and having an aperture 12 adapted for engaging a stud 75 13 on the die support. The clamp may be sprung outwardly for engaging said aperture 12 with the stud 13. Normally, the clamp acts merely as a keeper and the wire which is represented by the numeral 14 may be slipped 80 thereunder without springing the clamp from its stud 13.

It will further be noted that the winding line 8 is horizontally mounted upon a horizontal driven shaft 15 by means of a hub 85 or disk 16. The reel with a coil thereon can readily be removed in a horizontal direction without much effort or labor and the same constitutes a vast improvement over the usual vertical reels that are commonly used.

The main driving shaft of the machine is indicated at 17 which is adapted to be clutched to a co-axially driven shaft 18 through a clutch consisting of a clutch drum 19 and the usual movable cone member 20 which is operated by the usual shipper lever 21 secured upon a rod 22 extending longitudinally of the machine and suitably journaled in the frame thereof. A number of arms 23 rigidly secured upon the clutch rod 22 carry 100

counterweights 24 at their outer ends for automatically rotating the rod 22 for releasing the clutch at predetermined times as will later more fully appear.

5 The clutch rod 22 has also rigidly secured thereon a number of arms 25 which extend upwardly and in the opposite direction to the arms 23. These arms 25 carry a rod 26 upon their outer ends. The clutch may be thrown 10 out by elevating the rod 26. As the rod 26 extends a considerable distance lengthwise of the machine, it may be operated by an attendant at different points along the machine, so that the machine can be quickly stopped. 15 The clutch actuating rod 26 is adapted to be held in depressed condition by a latch 27 (Figures 3 and 8) pivoted to the frame as indicated at 28. This latch has a cut-away portion forming a shoulder 29 which engages 20 over one of the arms 25. A spring 30 suitably anchored at one end is connected at its other end to the latch 27 and is normally effected for shifting the latch over the arm 25 for holding the same in depressed position as 25 shown in Figure 3. A wire rod or cable 31 is also connected to the lower end of the latch 27. This cable extends in the opposite direction to the spring 30 and is attached to the lower end of a lever 32 pivoted intermediate 30 its ends upon a prop 33 extending from the frame of the machine. A spring 34 yieldingly anchors the lower end of the lever to the frame. The upper end of the lever 32 is provided with a loop 35 (Figure 2) through 35 which the wire passes to the first die. This loop is shown in exaggerated form, but it will be understood that in use it is sufficiently small to prevent kinks or loops in the wire from passing therethrough with the result that the lever is actuated for exerting a pull upon the cable or rod 31 for drawing the latch 27 from the arm 25 whereby the counterweights 24 will automatically actuate the clutch rod 22 for releasing the clutch and 40 stopping the machine. When the clutch is thuswise released, the rod 26 will be elevated and will automatically apply a brake 36 upon the drum clutch 19.

45 This brake 36 is in the form of a shoe pivoted at one end as indicated at 37. The other end of the shoe is suitably connected with an arm 25 by means of a yielding connection 38 or the like. When the rod 26 and arms 25 swing downwardly, the brake is released but when the same swing upwardly, the brake is applied.

50 In these wire drawing machines, the greatest reduction occurs at the first die 1 and consequently a greater force is required to 55 rotate the drum 2 that draws the wire through the first drum. The second die does not effect such a reduction. Consequently the drum 4 that draws the wire through the second die does not require as much force to rotate it as the first drum 2. However, the

second drum 4 must rotate faster than the first drum on account of the elongation of the wire, since the drums are of substantially equal diameter. In like manner, the third drum requires less force to rotate than the 70 second drum, but it must rotate faster on account of the elongation of the wire. In the past, it has generally been the practice to apply the power at the first drum that rotates the slowest and that requires the most power. 75 A great deal of waste power occurred in applying the power to the first drum. In order to avoid this waste of power, I have applied the power to the last drum or winding reel and used reduction gearing to drive the 80 slower rotating drums requiring greater force. For the gearing acts as a compound lever between the source of power and the drum that draws the wire through the first die which effects the greatest reduction. To 85 this end, the drive shaft 17 is located at the rear of the machine and is immediately geared to the reel shaft 15 by sprocket gearing 39. The shaft 15 is then geared by suitable sprocket gearing 40 to the rear drum 90 shaft 41. Of this sprocket gearing the sprocket wheel 40a on the shaft 41 will of course be slightly larger than the sprocket wheel 40b on the shaft 15 in order to decrease the speed of shaft 41. 95

Upon the shaft 41 there is a sprocket wheel 42 smaller than the sprocket wheel 40a that is geared by means of a sprocket chain 43 to a sprocket wheel 44 larger than the sprocket wheel 42 and which sprocket wheel 44 is secured upon the second drum shaft 45 whereby said shaft will be driven at a reduced rate of speed. Spaced from the sprocket wheel 44, there is a smaller sprocket wheel 46 which is geared by a suitable sprocket chain 47 to a larger sprocket wheel 48 upon the first drum shaft 49 for reducing the speed of said shaft. 100

105 While the operation of the machine is obvious from the foregoing description, it might be mentioned that when a wire is being drawn that contains a kink, such kink will engage the lever 32 and cause the upper end of said lever to be pulled rearwardly thereby swinging the latch 27 from engagement 110 with the clutch actuating mechanism allowing the counterweights 24 to drop and rotate the clutch rod 22 for releasing the clutch. As the counterweights 24 descend, the rod 26 and arms 25 will be elevated and through their connection with the brake the said brake will be applied. 115

120 I am aware that numerous details of construction may be varied through a wide range without departing from the principles of this invention, and I therefore do not purpose limiting the patent granted, otherwise than necessitated by the prior art.

125 I claim as my invention:

130 In a machine of the character described, a

driven shaft having a clutch drum thereon, a driving shaft having a clutch member for engaging said drum, a shipper lever for engaging said clutch member, a rod extending 5 longitudinally of the machine and connected to said shipper lever, a second rod extending parallel to the first rod, arms connecting said rods, a latch lever pivoted to said machine and having a shoulder for engaging one of 10 said arms, a spring for maintaining said shoulder in engagement with said arm, a brake for said clutch drum, a connection between said brake and one of said arms,

gravity weights connected to the first rod for automatically rotating the same for disengaging said clutch member, said latch lever normally holding said gravity weights in elevated position, and means whereby said latch lever may be released from said arm for allowing said counterweights to actuate said first mentioned rod for disengaging said clutch and elevating said arms and applying 70 said brake. 75

In testimony whereof I have hereunto subscribed my name.

PAUL W. DILLON.
